UNITED STATES PATENT OFFICE.

JESSE C. LEWIS, OF MILFORD, NEW HAMPSHIRE.

ADJUSTABLE TABLE.

No. 878,967.

Specification of Letters Patent.

Patented Feb. 11, 1908.

Application filed September 18, 1907. Serial No. 393,425.

To all whom it may concern:

Be it known that I, JESSE C. LEWIS, a citizen of the United States, residing in Milford, in the county of Hillsboro and State of New Hampshire, have invented new and useful Improvements in Adjustable Tables, of which the following is a specification.

This invention relates to an improved adjustable table adapted particularly for reading and writing purposes and especially intended for use in libraries, studies, reading-rooms and offices.

The nature of the invention is fully described below, and illustrated in the accompanying drawings, in which:—

Figure 1 is a plan view of my improved table with the arm-rests raised or extended and the top in a level position. Fig. 2 is a view of the under side with the parts in the same position. Fig. 3 is an end view with the parts in the same position. Fig. 4 is an end view with the arm-rests dropped and the top swung up into an inclined position. Fig. 5 is a vertical section taken on line 5—5, Fig. 2, showing the arm-rests dropped and the top swung up. Fig. 6 is an enlarged detail taken transversely through the horizontal groove in the top of the table. Fig. 7 is an enlarged detail taken longitudinally through said groove.

Similar numerals of reference indicate corresponding parts.

Reference numeral 10 refers to the side-bars, and 11 to the end-bars which constitute the supporting frame, and 12 represents suitable legs for supporting said frame. Pivotally secured at 13 to the upper edge of the front side-bar 10 of the frame is the flat table-top 14. This top is provided at its front edge with a guard-rest or bead 15 by means of which books are prevented from slipping off the front edge of the table, especially when the table is in the inclined position indicated in Figs. 4 and 5.

The surface of the table is provided between the guard-rest 15 and the rear edge—preferably somewhat nearer the rear edge—with the longitudinal groove 16 parallel with the guard-rest 15, and within this groove is 45 adjustably disposed a resting-bar 17. A series of passages 18 extend from the groove downward through the table-top 14 (Figs. 6 and 7), and adjusting screws 19 extend up through said passages and are connected at 50 their upper ends with plates 20 which are secured to the under side of the resting-bar

17. These screws move in threaded plates 21 secured to the under side of the table-top and extending across the passages 18 (Figs. 2, 6, and 7) and by means of said screws the 60 resting-bar 17 may be moved up into the position indicated in Figs. 4, 5, 6, and 7, and thus provide a resting place for books which lie on the table above the bar when said table is inclined; or by operating the screws 65 the resting-bar may be lowered into the position indicated in Fig. 3 in which it is flush with the surface of the table, if desired, as might be the case if the table were in a horizontal position. The table is adapted to be 70 swung up and held in such raised position by means of a swinging ratchet-bar which is pivotally secured at 22 to the under side of said table, and extends down through an opening 23 in a cross-bar 24 which is supported by the side-bars 10 of the frame. 75 This ratchet-bar consists of the two parts 25 and 26 which are hinged to each other at 27 and thus constitute a jointed ratchet-bar whose lower portion is adapted to swing 80 longitudinally with the table. When the table-top is horizontal, the upper portion 25 of the ratchet-bar lies in the opening 23, and the lower portion 26 is swung up under the cross-bar 24, and held preferably friction-tight in the horizontal position indicated in 85 Fig. 2 and thus kept practically out of sight. When the table-top is to be swung up the two parts of the ratchet-bar are swung into line, and as the table is lifted the toothed 90 edge of said bar is held by a spring 28 against and in engagement with a horizontal locking-rod 29 which is secured to the cross-piece 24 and extends across the opening 23, said spring being secured at one end at 30 to 95 the rear side-bar 10—all as illustrated in Figs. 2 and 5. The table-top has pivoted at 31 to its under side behind the frame a depending longitudinal board 32 (Fig. 5), and the top has rigidly secured to its under side 100 within the frame and next the end-bars 11 a pair of substantially segment-shaped boards or guards 33 (Figs. 2, 3, 4, and 5). By means of the swinging board 32 and the transverse boards or guards 33, when the 105 table is swung up a finish is provided whereby the parts within the frame are hidden.

Pivotally secured at 34 to the upper edge of the front side-bar 10 are a pair of leaves 35 whose inner edges are shaped or hollowed out at 36 so that when said leaves are raised 110 and in a horizontal position there is room

- between them for the form of the person sitting at the table. These leaves, which are adapted to be used as arm-rests, or for holding a lamp, for example, are supported 5 in such horizontal position by means of horizontal tubes 37 which are supported slid- 60 ingly by horizontal rods 38, the rear ends of said rods being secured to the rear side-bar 10, and the tubes 37 extending through and 65 being supported slid- 10. Preferably I apply small blocks or plates 39 to the under surfaces of the arm- 70 rests 35, said plates resting directly on the tubes when they are drawn forward for the 75 purpose of supporting the arm-rests. Suitable stops 40 are applied to the tubes 37 be- 80 hind the front side-bar 10 whereby said tubes are prevented from becoming detached from the rods 38.
- 20 Preferably I apply a small drawer 41 centrally to the frame of the table between the arm-rests. It will thus be seen that the table when its top is raised can support at least two rows of books which are prevented 25 by the guard-rest 15 and the bar 17 from sliding off the table or into contact with each other; that when such table-top is in a raised position the internal construction is hidden by the parts 32 and 33; that if desired the 30 surface of the top of the table may be ren- 85 dered unbroken by lowering the bar 17 into its groove; that when the table-top is hori- 90 zontal the ratchet-bar may be swung up into an inconspicuous position; and that leaves 95 35 may be swung up into level positions and used either for supporting the arms or for adding to the available area of the top, or may be swung down out of the way, as desired.
- 40 Having thus fully described my invention, what I claim, and desire to secure by Letters Patent is:—
1. In an adjustable table, a stationary supporting frame, a table-top hinged at its 45 front edge to the front portion of said frame, mechanism for supporting said table-top when raised in an inclined position, and a longitudinal guard-board pivotally connected at its upper edge with the under side 50 of the table-top at an appreciable distance in front of the rear edge of said table-top and hanging substantially vertically therefrom behind and near the frame, and adapted when the table-top is raised to provide a 55 finish between said table-top and frame and to hang snugly against the latter.
  2. In an adjustable table, a stationary

supporting frame, a table-top hinged at its front edge to the front portion of said frame, a jointed ratchet-bar hinged at its upper end 60 to the under surface of the table-top and hanging vertically therefrom, a locking-rod supported by the frame of the table, and a spring holding the ratchet-bar normally in engagement with the locking-rod, whereby 65 when the table-top is level the lower end of the ratchet-bar may be swung up into a substantially horizontal position.

3. In an adjustable table, a stationary supporting frame, a table-top hinged at its 70 front edge to the front portion of said frame and provided with a horizontal longitudinal groove in its upper surface said groove being intersected by passages in the table-top which extend downward through said table- 75 top, mechanism for supporting said table-top in an inclined position, a horizontal resting-bar in said groove, vertically disposed adjusting screws extending upward through said passages into engagement with said 80 resting-bar, and screw-threaded plates secured to the under side of the table-top at the lower ends of said passages and adapted to receive the threaded portions of said 85 screws, whereby the resting bar may be raised and lowered in a vertical line with relation to the surface of the table-top, for the purpose set forth.

4. In an adjustable table, a supporting frame, a table-top supported by the frame, 90 arm-rests pivotally secured at their rear edges to the front edge of the table-top, and telescopically arranged rods horizontally supported by the frame and with their forward tubular portions extending slid- 95 ingly through the front wall of said frame and adapted to be drawn forward and act as supports for the arm-rests.

5. In an adjustable table, a supporting frame, a table-top, arm-rests hinged to the 100 front edge of the table-top near its opposite ends and with their inner edges hollowed out to receive between them the form of the person sitting at the table when said arm- 105 rests are raised, and means for sustaining the arm-rests in a raised horizontal position.

In testimony whereof I have signed my name to this specification in the presence of two subscribing witnesses.

JESSE C. LEWIS.
